WALTER JOHNSON, OF MIDDLETOWN, CONNECTICUT.

TOY AEROPLANE.

1,311,351.

Specification of Letters Patent. Patented July 29, 1919.

Application filed February 6, 1919. Serial No. 275,368.

To all whom it may concern:

Be it known that I, WALTER JOHNSON, citizen of the United States, residing at Middletown, in the county of Middlesex and State of Connecticut, have invented a new and useful Improvement in Toy Aeroplanes, of which the following is a specification.

This invention relates to the construction of a tractor aeroplane of the biplane, heavier than air, type which is designed for the amusement of children and which may be carried in the hand, flown as a kite or provided with a light spring or elastic motor for rotating the air screw and imparting a short flight.

The object of the invention is to provide a very simple and cheap toy of this character which may be readily collapsed and folded for packing and transportation and instantly unfolded and locked in erect shape.

This object is attained by blanking the parts of pieces of cardboard or the like sheet material which is thin and somewhat rigid, and fitting the pieces together and interlocking them in such manner that they will collapse and fold flat for packing in an envelop and unfold for use without disconnecting any of the pieces, and may be locked in erect shape by the simple turning of a single piece.

Figure 1 of the accompanying drawings shows a plan of the toy opened or in erect shape. Fig. 2 shows a side view of the same. Fig. 3 shows a plan of the toy collapsed and folded flat and with the air screw detached. Fig. 4 shows an edge view of the toy collapsed. Fig. 5 shows a front view of the toy opened and with the air screw omitted.

In constructing this device two pieces of cardboard or other thin, stiff, sheet material are each cut to approximate the outlines of the fuselage 1, nose 2, shock absorbing or under carriage 3, tail 4, tail skid 5, tail fin 6 and rudder 7. These, forming the side pieces, are arranged edgewise a little distance apart and are connected across the top of the fuselage by the top main plane 8 and lower down by the bottom main plane 9, which planes are cut from thin, stiff, sheet material. The leading edges and trailing edges of the planes are notched and fitted into notches in the edges of the pieces forming the sides of the fuselage, the planes being a little wider than the spaces into which they are fitted so that they will be cambered when in place. At the tail the side pieces

are connected by a piece of sheet material cut to approximate the shape of flat tail planes 10, this piece passing flatwise through slots and being notched on its leading edge 60 to prevent its removal when in place. At the nose the side pieces are connected by a horizontal nose plane 11 of sheet material which passes through slots in the side pieces and is notched on its leading edge to prevent its removal. The nose plane has two perforations 12 and threaded through these is a pin 13 which forms the shaft of the air screw 14. The air screw is desirably cut from a single piece of sheet material to approximate shape and folded on itself at the middle to give the required pitch to the blades.

In the middle of the top main plane is a perforation 15 and in the middle of the bottom main plane is a perforation 16. Located between the planes with its apex 17 projecting through the perforation in the top plane and a stem 18 extended through the perforation in the bottom plane is a 80 triangular king-post or bracing strut 19. When the planes are separated or opened and this king-post is turned parallel with the longitudinal axis of the planes or transversely of the side pieces, the lower edge of 85 the triangle rests upon the bottom plane and the apex of the triangle engages the walls of the perforation in the top plane in such manner that the planes cannot be closed together, and when the planes are so held 90 the whole structure is locked open and in erect shape. When the king-post is turned transversely of the planes and parallel with the side pieces, the planes may be folded together and with the folding of the planes 95 the whole structure collapses and folds flat so that it may be readily packed in an envelop. The machine illustrated consists of but eight pieces of cardboard which are so joined that they may be folded or unfolded 100 without separating any of the pieces or breaking any of the joints, and all that is necessary to lock the parts open is to turn the triangular king-post in one direction, and to unlock the parts so that they will 105 fold together it is only necessary to turn the king-post a quarter turn.

The invention claimed is:—

1. A toy aeroplane having a fuselage, main, nose and tail planes formed of pieces 110 of thin, stiff, sheet material jointed together so that without disconnecting any of the

pieces they may be folded together flatwise or opened apart, and means for locking the pieces in opened relation.

2. A toy aeroplane having a fuselage formed of flat side pieces of sheet material, with main, nose and tail planes of sheet material jointed to the side pieces so that the parts without disjoining may be folded upon each other flatwise or opened apart, and means for holding the main planes separated and maintaining the parts in opened relation.

3. A toy aeroplane made of thin, stiff, sheet material having side pieces, main planes connecting the side pieces, a plane connecting the side pieces at the nose, a plane connecting the side pieces at the tail, and adjustable means for retaining the main planes separated.

4. A toy aeroplane made of thin, stiff, sheet material having side pieces, cambered main planes extending across and jointed to the side pieces, a horizontal plane extending across and jointed to the side pieces at the nose, a horizontal plane extending across and jointed to the side pieces at the tail, and means for retaining the main planes separated and parallel.

5. A toy aeroplane having a fuselage, main, nose and tail planes cut from thin,

stiff, sheet material jointed so that they may be folded flat or opened apart, and a triangular bracing strut connecting the main planes and adapted when turned to one position to hold the planes apart and when turned to another position to permit the planes to fold together.

6. A toy aeroplane having a fuselage with nose, under carriage tail, tail fins and rudders formed of two sheets of cardboard cut to shape, a pair of main planes extending across and notched into the fuselage, a horizontal plane extending across and notched into the nose, a horizontal plane extending across and notched into the tail, a triangular king-post connecting the main planes and retaining them apart when in one position and allowing them to collapse when in another position, and an air screw carried by the nose plane.

7. A toy aeroplane formed of pieces of cardboard notched into each other and adapted to be folded together and opened apart without disengagement, and a piece of cardboard adjustably arranged between the pieces and shaped to lock the pieces opened or permit them to be folded together flatwise, according to the position to which said locking piece is adjusted.

WALTER JOHNSON.
